CASING FOR A HAND-HELD INTERACTIVE COMPUTER TERMINAL

Charles Michael Ault, 11 Devereaux St.,
Arlington, Mass. 02174

Filed Mar. 11, 1974, Ser. No. 449,680

Term of patent 14 years

Int. Cl. D18—01
U.S. Cl. D26—5 C

FIG. 1

FIG. 2

FIG. 3

FIG. 4

FIG. 7

FIG. 5

FIG. 6

FIG. 1 is a front elevational view of a casing for a hand-held interactive computer terminal, showing my new design;

FIG. 2 is a right side elevational view thereof;

FIG. 3 is a bottom plan view thereof;

FIG. 4 is a top plan view thereof;

FIG. 5 is a rear elevational view thereof;

FIG. 6 is a left side elevational view thereof; and

FIG. 7 is a fragmentary cross-sectional view taken along the line 7—7 of FIG. 4.

I claim:

The ornamental design for a casing for a hand-held interactive computer terminal, substantially as shown.
